INTERCOMMUNICATION SYSTEM

Roswell H. Herrick, Oak Park, Ill., assignor to
 Automatic Electric Laboratories, Inc., Chicago,
 Ill., a corporation of Delaware

Application March 25, 1944, Serial No. 528,030

15 Claims. (Cl. 179—38)

The present invention relates to intercommunication systems having a plurality of stations remotely located and particularly to switching circuits for such systems. The invention has been illustrated in connection with a system in which each station is provided with a microphone, a loudspeaker, amplifiers, power supply, control keys, and switching relays. Each station has a station selecting key corresponding to each other station. There is also a selecting relay corresponding to each other station for effecting the desired connections between stations. Auxiliary relays which are controlled over the same conductors used for communication are used for signalling and for controlling the amplifiers.

The principal object of the invention is to provide an efficient switching arrangement having a number of novel features such as the completion of a communication circuit without the necessity of the called party knowing the identity of the calling station, assuring privacy of the circuit thus established, automatic signalling, and the provision of a visual busy signal.

A feature of the invention is the elimination of the delay usually required for the amplifiers at the called station to warm up by energizing them at the time the call is initiated so that conversation may proceed immediately upon answering, but maintaining the amplifiers inactive until the completion of a connection to eliminate background noises created by stray coupling and to prevent the calling party from overhearing conversation in the vicinity of the called station prior to answering.

Other objects and features of the invention will appear upon a further perusal of the specification and the accompanying drawings in which:

Fig. 1 is a schematic wiring diagram of two complete stations with the necessary interconnections.

Fig. 2 is a modification of Fig. 1 that affords complete privacy of the conversation and eliminates the common lead of Fig. 1.

Referring to the drawings, the amplifiers indicated may be any conventional design having the requisite gain and output capabilities for the purpose intended and provided with transformers to match the impedances of the input and output circuits. The amplifier tubes are preferably of the quick heating type. Voice operated switching means to prevent the output of the loudspeaker from affecting the output of the amplifier associated with the microphone are indicated in block form.

The station selector keys may be any conventional design. These keys must be the locking type for Fig. 1. The non-locking type is preferred for Fig. 2. The other keys for both figures are preferably non-locking.

The power supply indicated in block form can be any conventional design that will furnish the

filament and plate voltages for the amplifiers and voice operated switching system and will also supply an isolated D. C. voltage for operating a relay at the called station over the talking leads.

- 5 The power supply must also furnish a low voltage for operation of the audible and visual signals. A separate transformer is shown in the drawings for operating the switching relays. This transformer must be continuously excited.
- 10 The method of operation will now be described briefly. Referring to Fig. 1, each station is equipped with a station selecting key corresponding to each other station. A selecting relay is also provided for each selecting key. One of the input terminals of the "in" amplifier, in series with a control relay, and one of the output terminals of the "out" amplifier at each station are multiplied to contacts on the corresponding selecting relays at every other station and are also multiplied to contacts on each of the selecting relays associated with that station. The other input terminal of the "in" amplifier and the other output terminal of the "out" amplifier, in series with a source of direct current, are connected to a lead which is common to all of the stations. The operation of a selecting key operates one of the selecting relays to complete a circuit between the "in" amplifier at the calling station and the "out" amplifier at the called station, and to complete a second circuit between the "out" amplifier at the calling station and the "in" amplifier at the called station. The relay in series with the input of the "in" amplifier at the called station is operated by the direct current source in series with the output of the "out" amplifier at the calling station. This relay operates and energizes the amplifiers at the called station and starts the audible signal. The amplifiers at the calling station are energized by the operation 25 of a relay that is controlled by the selecting relays or by an answer key. Operation of the answer key at the called station causes the operation of the corresponding relay at the called station which enables the use of the amplifiers and stops the audible signal. The communicating circuit is now complete and will remain in this condition until the selecting key is restored at the calling station.
- 30 Referring now to Fig. 2, each station is equipped with a station selecting key and a selecting relay corresponding to each other station as in Fig. 1. Both input terminals of the "in" amplifier, in series with a control relay, are multiplied to contacts on the corresponding selecting relays at 35 every other station. Both output terminals of the "out" amplifier, in series with a source of direct current and a lamp, are multiplied to contacts on each of the selecting relays associated with that station. The operation of a 40 selecting key operates one of the selecting relays which completes a circuit between the "out" am-

- 55
- 60

plifier at the calling station and the "in" amplifier at the called station to establish a communicating circuit and to operate the control relay at the called station. The audible signal at the called station is operated and the amplifiers energized. When the call is answered by operating the answer key all of the selecting relays at the called station are momentarily associated with their corresponding stations and the relay that corresponds to the calling station is caused to operate thereby connecting the "out" amplifier at the called station to the "in" amplifier at the calling station. A second communicating circuit is thus established. The connections will remain in this condition until released by the operation of the release keys at the connected stations.

The method of operation will now be described in detail. Referring to Fig. 1, when a party at station 1 desires to communicate with another party at station 2, he operates the station selector key 101 assigned to station 2, closing the circuit to relay 102. Relay 102 operates and closes the circuit to relay 103. Relay 103 operates, prepares its locking circuit, removes a short-circuit from the output of the "out" amplifier, opens the circuit to the audible signal 104, and closes the A. C. supply to the power supply unit. Energizing the power supply causes the pilot lamp 105 to light, prepares the amplifiers for use, and produces a D. C. voltage between leads 106 and 107. The previous operation of relay 102 closed a circuit from the output transformer of the "out" amplifier of station 1, through contacts 108 to relay 109 at station 2 through line 110 of the connecting cable, through relay 109 and the input transformer of the "in" amplifier at station 2 to the common lead. The other end of the output transformer at station 1 is connected to the common lead through the isolated D. C. source in the power supply. A direct current therefore flows through line 110, relay 109, and returns over the common lead causing relay 109 to operate. Relay 109 operates, removes a short-circuit from the output of the "in" amplifier at station 2, prepares a locking circuit to relay 111, and closes the A. C. supply to the power supply unit at station 2. Energizing the power supply unit causes the pilot lamp 112 to light and starts the audible signal 113 at station 2. The D. C. voltage produced between leads 114 and 115 at station 2 will cause a direct current to flow through the output transformer of the "out" amplifier at station 2, over line 116 of the connecting cable, through contacts 117 of relay 102, through relay 118 and the input transformer of the "in" amplifier at station 1, and returning to the power supply unit at station 2 via the common lead causing relay 118 to operate. Relay 118 operating, closes a locking circuit to relay 103 and removes a short-circuit from the output of the "in" amplifier at station 1.

The called party at station 2 will respond to the signal by momentarily operating the answer key 119, causing relay 111 to operate and lock through contacts 120 to contacts 121 of relay 109. Relay 111 operating, opens the circuit to the audible signal 113 and removes a short-circuit from the output of the "out" amplifier at station 2. The complete two-way communication circuit is now established. Signals generated by the microphone at station 1 are amplified by the "out" amplifier at station 1 and conveyed by lead 110 and the common lead of the connecting cable to the input of the "in" amplifier at station 2 where

they are further amplified before being reproduced by the loudspeaker at station 2. In a similar manner signals generated by the microphone at station 2 are conveyed by lead 116 and the common lead of the connecting cable to station 1 where they are further amplified by the "in" amplifier and reproduced by the loudspeaker. The condensers across relays 109 and 118, and across the D. C. voltage supply for these relays provide a low impedance path for audio frequencies. Although the amplifiers at the called station are prepared for operation at the instant that a call is initiated the calling party cannot overhear any conversation taking place in the vicinity of the microphone at the called station before the call is answered due to the short-circuit across the output of the "out" amplifier, but the loudspeaker at the called station will respond to signals produced by the microphone at the calling station.

When the conversation is completed the selector key at the calling station is restored, opening the circuit to relay 102. Relay 102 restoring opens the circuits to relays 109 and 118 at contacts 108 and 117, respectively. Relays 109 and 118 restore and open the locking circuits to relays 103 and 111. Relays 103 and 111 restore and disconnect the A. C. supply from their associated power supply units. The pilot lamp 112 at the called station remains lit until the calling party releases the connection to inform the called party that his microphone is still active.

Referring now to Fig. 2, when a party at station 1 desires to communicate with a party at station 2, he momentarily operates the station selector key 201 corresponding to station 2 thus closing the circuit to relay 202. Relay 202 operates, closes its locking circuit through contacts of the release key 203, and closes a circuit to relay 204. Relay 204 operates, prepares its locking circuit, opens the operating circuit to relay 202 at contacts 205, opens the circuit to the audible signal 206, removes a short-circuit from the output of the "out" amplifier, and closes the A. C. supply to the power supply unit. Energizing the power supply unit prepares the amplifiers for use and causes a D. C. voltage to be produced between leads 207 and 208. This voltage causes a current to flow over a circuit previously closed by the operation of relay 202 to operate relay 209 at the called station. This circuit can be traced from lead 207 through the output transformer of the "out" amplifier at station 1, contacts 210, line 211, relay 209, the input transformer of the "in" amplifier at station 2, line 212, contacts 213, and the pilot lamp 214 to lead 208.

The pilot lamp 214 will light and relay 209 will operate. In the event that station 2 is in use a similar circuit to relay 209 would have been previously established from another station. Relay 209 would then only draw one half of its normal current from each station causing the pilot lamps at these stations to dim, thus indicating to the calling party that the called station is in use. Now assuming station 2 is idle, relay 209 operates, removes a short-circuit from the output of the "in" amplifier at station 2, prepares a locking circuit for relay 215, and closes the A. C. supply to the power supply unit at station 2. Energizing the power supply unit prepares the amplifiers for use, starts the audible signal 216, and causes a D. C. voltage to be produced between lines 217 and 218. When the called party at station 2 responds to the call he momentarily operates the answer key 219, thus closing the circuit to relay

220. Relay 220 operates, prepares a circuit to each line relay from its associated line, and closes a circuit to the line relay corresponding to the calling line, in this case relay 221. This circuit can be traced from the secondary of transformer 222 through contacts of the release key 223, contacts 224, line 212, contacts 213, contacts 225, line 226, contacts 227, and through relay 221 to the other side of the secondary of the transformer 222. The circuits to all of the other line relays at station 2 will be open at the contacts of the corresponding line relays at the other stations. Relay 221 operates over the circuit just traced, closes its locking circuit through contacts on the release key 223, closes a circuit to relay 215, and connects the output of the "out" amplifier at station 2 through lines 226 and 228 to the input of the "in" amplifier at station 1. The D. C. voltage between leads 217 and 218 causes a direct current to flow through this circuit and through relay 229. Relay 215 operates, closes its locking circuit through contacts 230 to contacts 231 on relay 209, opens the circuit to the audible signal 216, removes a short-circuit from the output of the "out" amplifier at station 2, and opens the circuit to relay 220. Relay 220 restores and disconnects the line relays from their associated lines. This entire operation actually takes place in a few milli-seconds while the answer key 219 is operated by the called party. Relay 229 operates over the circuit previously described, closes the locking circuit to relay 204 at contacts 232, removes the short-circuit from the output of the "in" amplifier at station 1, and opens the tie between the input of the "in" amplifier and the output of the "out" amplifier at contacts 225. The complete communication circuit is now established and conversation can proceed. The signals produced by the microphone at station 1 are amplified by its associated amplifier and conveyed to the input of the "in" amplifier at station 2 over lines 211 and 212. In like manner, signals produced by the microphone at station 2 are amplified by its associated amplifier and conveyed to the input of the "in" amplifier at station 1 over lines 226 and 228. The condensers across relays 209 and 229, and across the D. C. voltage supply for these relays provide a low impedance path for audio frequencies. Although the amplifiers at the called station are prepared for operation at the instant that a call is initiated the calling party cannot overhear any conversation taking place in the vicinity of the microphone at the called station before the call is answered because this portion of the communicating circuit is open at contacts 233 and 234 of the line relay 221. The short-circuits across the outputs of the amplifiers is an additional precaution to prevent any signal from reaching the loudspeakers due to stray coupling before a connection is established. If either station 1 or station 2 is called by a third station while they are connected, the third station will have the output of its "out" amplifier connected to the input of the "in" amplifier at the station called, but the line relay at the called station corresponding to the third station will not be operated and will therefore prevent the party at the third station from overhearing the conversation already in progress, but will permit the third party to speak to the party he called. If the message is urgent the first connection established can be released and the answer key operated at the station called by the third party to establish a new connection.

When the conversation between stations 1 and 2 is terminated the connection is released by the momentary operation of the release key at each station. Assuming that the party at station 1 disconnects first, operation of the release key 203 opens the locking circuit to relay 202. Relay 202 restores, opens the operating circuit to relay 204, and disconnects the output of the "out" amplifier and the D. C. voltage supply from lines 211 and 212 thus opening the circuit to relay 209. Relay 204 remains locked to relay 229 to prevent re-operation of the audible signal 206. Relay 209 restores, opens a multiple circuit to relay 215 and short-circuits the output of the "in" amplifier at station 2. When the release key 223 at station 2 is operated momentarily, the locking circuit to relay 221 is opened. Relay 221 restores, opens the circuit to relay 215 and disconnects the output of the "out" amplifier and the D. C. voltage supply from lines 226 and 228 thus opening the circuit to relay 229. Relay 215 restores and disconnects the power supply unit at station 2 from the A. C. supply. Relay 229 restores and opens the locking circuit to relay 204. Relay 204 restores and disconnects the power supply unit at station 1 from the A. C. supply.

It is to be understood that the form of the invention herewith shown and described is to be taken as a preferred example of the same, and that various modifications may be resorted to without departing from the spirit of the invention or the scope of the subjoined claims.

Having thus described the invention, what is claimed as new and desired to secure by Letters Patent is:

1. In an intercommunicating system including a plurality of stations, each comprising voice receiving and transmitting means, a direct current source associated with each said transmitting means, a relay associated with each said receiving means, conductors for each station, switching means at each station, said switching means being operated at one station to selectively connect the transmitting means of said one station and the receiving means of any other station via said conductors to simultaneously complete a talking circuit therebetween and energize the relay at said other station by the source of direct current at said one station over the same said conductors.
2. In an intercommunicating system as claimed in claim 1, a lamp in series with each said direct current source, and circuit arrangements causing the lamp at said one station to indicate if said other station is in use when the transmitting means of said one station is connected to the receiving means of said other station.
3. In an intercommunicating system including a plurality of stations, each comprising voice receiving and transmitting means, station selecting keys, an answer key, and an audible signal, means controlled by the operation of one of said selecting keys for connecting one of the stations to another to complete a communication circuit between the transmitting means of said one station and the receiving means of the other station, relay switching means at said other station also controlled by the operation of the associated selecting key at said one station to operate said audible signal at said other station and operated in response to the operation of said answer key at said other station to stop the operation of said audible signal.
4. In an intercommunicating system including a plurality of stations, each comprising voice

receiving and transmitting means, station selecting keys, and an answer key, means responsive to the operation of a selecting key at one of said stations for connecting it with another of said stations and enabling the transmitting means at said one station and the receiving means at said other station, and means responsive to the operation of said answer key at said other station enabling the transmitting means at said other station and the receiving means at said one station.

5. In an intercommunicating system including a plurality of stations, each comprising voice receiving and transmitting means, amplifying means therefor, and station selecting keys, relay switching means at each station operative in response to the operation of any one of said selecting keys at one station to connect that station with another station and to energize the amplifying means at said one station and at the station associated with said selecting key.

6. In an intercommunicating system including a plurality of stations, each comprising voice receiving and transmitting means, amplifiers for said receiving and transmitting means, station selecting keys, and an answer key, relay switching means at each station operative in response to the operation of any one of said selecting keys at one station to connect that station with another station and to energize the amplifiers at said one station and at the station associated with said selecting key and to enable operation of the transmitting means at said one station and the receiving means at said other station, said relay switching means operated in response to the operation of said answer key at said other station to enable operation of the transmitting means at said other station and the receiving means at said one station.

7. In an intercommunicating system including a plurality of stations, each having an input and an output circuit, and a selecting relay corresponding to each other station, means at each station for at times associating the input and output circuits thereof, conductors associated with the input circuits of each station and multiplied to the corresponding selecting relays at every other station, means for operating a selecting relay at one station to connect the output circuit of said one station to the input conductor of another station to thereby associate the input conductors of said two stations, means for causing said selecting relays at said other station to test all of said conductors and to connect the output circuit of said other station to the input conductor of said one station which is identified by said association between the input conductors of said two stations.

8. In an intercommunicating system as claimed in claim 7, a release key at each station, and circuit arrangements maintaining said connections under control of the release keys of the connected stations.

9. In an intercommunicating system as claimed in claim 7, circuit arrangements preventing the re-operation of said selecting relays at said other station while said other station is connected to said one station to assure privacy of said connection.

10. In a telephone system, a plurality of stations, a relay at each station corresponding to each other station, means for extending a connection from a calling one of said stations to a called one of said stations, means for causing all of the relays at the called station to be associated with their corresponding stations and for operating only that relay at the called station which corresponds to the calling station.

11. In an intercommunicating system, a plurality of stations, a relay at each station corresponding to each other station, means for operating any one of the relays at a calling one of said stations to connect that station with a called one of said stations corresponding to said one relay and for signalling said called station, and means at the called station operated when the party thereat responds to said signal for causing all of the relays thereat to be associated with their corresponding stations and operating only that relay which corresponds to the calling station.

12. In an intercommunicating system, a plurality of stations, each having an input and an output circuit, and a selecting relay corresponding to each other station, conductors associated with the input circuits of each station and multiplied to the corresponding selecting relays at each other station, means including said relays for connecting the output circuit of any one of said stations to the input circuit of any other station, means at said other station for connecting a voltage source between the input circuit of said other station and said conductors through the selecting relays at said other station, circuit arrangements at said one station to complete a circuit only to the selecting relay at said other station that corresponds to the said one station.

13. In an intercommunicating system as claimed in claim 3, a direct current source associated with the transmitting means at said one station, said relay switching means being associated with the receiving means at said other station so as to be controlled by said source over the same conductors over which said communication circuit is completed.

14. In an intercommunicating system including a plurality of stations, each comprising voice receiving and transmitting means, station selecting keys, an answer key, and an audible signal, means controlled by the operation of one of said selecting keys for connecting one of the stations to another to complete a pair of oppositely directed communication channels between the transmitting and receiving means of said two stations, one of said channels being disabled, means at said other station also controlled by the operation of the associated selecting key at said one station to operate said audible signal at said other station, and means operated in response to the operation of said answer key at said other station to stop the operation of said audible signal and to enable said one channel.

15. In an intercommunicating system including a plurality of stations, each comprising voice receiving and transmitting means, station selecting keys, an answer key, and an audible signal, means controlled by the operation of one of said selecting keys for connecting one of the stations to another and enabling the transmitting means at said one station and the receiving means at said other station, means at said other station also controlled by the operation of the associated selecting key at said one station to operate said audible signal at said other station, and means operated in response to the operation of said answer key at said other station to stop the operation of said audible signal and enable the transmitting means at said other station and the receiving means at said one station.
